UNITED STATES PATENT OFFICE.

ALBERT N. WOODRUFF, OF NEW YORK, N. Y.

COPY-HOLDER.

1,345,978.

Specification of Letters Patent.

Patented July 6, 1920.

Application filed November 20, 1919. Serial No. 339,325.

To all whom it may concern:

Be it known that I, ALBERT N. WOODRUFF, a citizen of the United States, and a resident of the city of New York, borough of 5 Manhattan, in the county and State of New York, have invented a new and Improved Copy-Holder, of which the following is a full, clear, and exact description.

The present invention relates to new and 10 useful improvements in copy holders and it pertains more particularly to copy holders of the movable marker type.

It is the primary object of the invention 15 to provide a copy holder in which the marker is given a step-by-step movement relative to the copy.

It is a further object of the invention 20 to provide a suitable means whereby the step-by-step movement of the marker may be varied to accommodate the space between the lines of different copies.

It is a still further object of the invention 25 to provide a clamp by means of which the copy may be securely held on the holder.

Referring to the drawings—

Figure 1 is a front elevation of a copy 30 holder constructed in accordance with the present invention;

Fig. 2 is a sectional view taken on the line 2—2 of Fig. 1;

Fig. 3 is a sectional view on the line 3—3 of Fig. 2;

Fig. 4 is a fragmentary detail view 35 partly in elevation and partly in section of a portion of the device;

Fig. 5 is a rear view partly in section of a modified form of the invention;

Fig. 6 is a fragmentary detail view of a 40 portion of the modified form of the invention.

Referring more particularly to the drawings, the reference character 5 designates a base which may be formed of wood, metal, or other suitable material. Pivoted to the 45 sides of the base at one end thereof, is a bracket 6, the pivotal point of said bracket being designated by the reference character 7. Projecting from the inner face of the bracket 6, at a point below its upper edge 8, 50 is a supporting bed 9. The upper edge of this supporting bed 9 is depressed into a channel form as indicated by the reference character 10, and projecting from the under face of the supporting bed 9 behind the de- 55 pressed channel 10, is a flange 11. This flange 11 is provided with a rolled edge in

such a manner as to form eyes 12, in which is pivoted a supporting brace or standard 13. This supporting brace or standard 13 has its lower end bent to form a foot 14, 60 adapted to engage the top face of the base 5, and said foot is bent downwardly as at 15, to engage the side of the base 5, as best shown in Fig. 2. Secured to the rear face of the supporting bed 9, is a bearing mem- 65 ber 16, and pivotally mounted in said bearing 16, is a bail 17, which projects beyond the side of the supporting bed 9 and extends parallel thereto as designated by the reference character 18. Projecting from the parallel portion 18 of the bail is a right- 70 angular extension 19, and said right-angular extension 19 is adapted to lie within the channel 10 heretofore mentioned and as shown in Fig. 2, to retain the copy in position on the supporting bed 9. The reference character 20 designates a spring, one 75 end of which is secured as at 21, to the parallel portion 18 of the bail, the other end of the spring being secured to the sup- 80 porting bed 9.

By the above-outlined construction, it will be apparent that the right-angular extension 19 is maintained at all times within the channel 10, the spring 20 serving this pur- 85 pose.

Mounted in the bracket 6 and flange 11, as 90 more clearly shown in Figs. 2 and 3, is a rod 22, said rod being centrally disposed with respect to the side edges of the sup- 95 porting bed 9, and mounted near the right- hand side edge of the supporting bed 9 is a rod 23, which latter rod extends parallel to the rod 22. Slidably mounted on these rods 22 and 23, is a plate 24, said plate hav- 100 ing its ends bent around the rods as indicated by the reference character 25. Pivot- ally secured as at 26, is a lever 27, and said lever 27 has an operating portion 28, which extends beyond one end of the plate 24. 105 This operating lever 28 is bent at right an- gles to the main body of the lever 27, and projects through an opening 29 in said plate. Carried by the lever 27, is a second plate 30, and said plate 30 is provided with an open- 110 ing 31, through which the rod 32 passes. This plate 30 and lever 27 are angularly dis- posed with relation to the rods 22, 23 and 32, as best shown in Fig. 4. The reference character 33 designates a spring, the lower free end 34 of which engages the plate 30 to maintain it in a plane parallel with the

angular plane which the lever occupies. To maintain the lever 27 in the angular plane, a spring 35 is employed, one end of which is secured as at 36, to the edge of the plate, the other end being secured as at 37, to said lever.

Owing to the angular disposition of the plate 30, it will be seen that the rod 32 is free to pass through the opening 31 in one direction, but as the rod moves in the opposite direction, a binding or gripping action of the plate 30 on the rod is obtained.

The rod 32 is slidably mounted in the bracket 6 and the flange 11, and said rod is provided on its lower end with an operating button 38. Connected to the rod 32, is an arm 39, and connected to the arm 39, is a spring 40, the other end of which is secured, as at 41, to the inner end of the bail member 17. By this construction, it will be seen that as the operating button 38 of the rod 32 is pressed, the rod is reciprocated longitudinally of the supporting bed 9, and against the action of the spring 40. As the rod is released, the spring 40 returns the rod to its normal position, and owing to the binding action of the plate 30 on said rod 32, the plate 24 will likewise be moved along the rods 22 and 23. If the operating lever 28 is depressed, it will be seen that the gripping action of the plate 30 on the rod 32, is released, thus permitting a free movement of the plate 24 longitudinally of the rods 22 and 23. In this manner, the plate 24 may be moved to any desired position throughout the length of the supporting bed 9.

The reference character 45 designates a movable marker which is adapted to travel over the surface of the copy mounted on the bed 9, and said marker is carried by means of a rod 46, which in turn is secured to the plate 24 in such a manner that as the plate moves longitudinally of the rods 22 and 23, as heretofore described, the marker will be moved downwardly of the copy. This rod 46 passes around the rear of the plate 24, as shown in Fig. 3, and is secured thereto in any desired manner. The marker 45 is pivotally mounted on the rod 46, and is maintained in contact with the copy by means of a coil spring 47, one end of which is secured to the rod 46, as at 48, the other end engaging the finger portion 50 of the marker, as indicated by the reference character 49.

In devices of this character it is desired to have the marker so constructed that a step-by-step movement may be varied to copy articles in which the spaces between the lines differ, and to obtain this result, the supporting bed 9 is provided in one of its side edges with a screw-threaded bolt 52. This bolt 52 engages in the screw-threaded opening of a lug 53 integrally formed on the end of a plate 54. This plate 54 has an angular edge 55, and said angular edge is

adapted to be adjusted with relation to the stop 56 carried on the rod 32. By this construction, it will be seen that as the screw-threaded bolt 52 is rotated by means of its knurled head 57, the angular edge 55 of the plate 54 is adjusted relatively to the stop 56, in such a manner that the throw of the reciprocating rod 32 may be varied in order that the distance of movement of the marker 45 may also be varied.

In the modified form of the invention shown in Figs. 5 and 6, the supporting bed 9 is provided on its rear face with two rods 60 and 61, said rods being mounted in the brackets 62 and 63 at the upper and lower ends, respectively, of the bed. In this form of the invention, a spring 64 is secured as at 65, to a stop 66 carried by the rod 60, and said spring 64 is adapted to return the rod 60 to its normal position after the same has been depressed by means of its operating head 67.

Slidably mounted on the two rods 60 and 61, is a plate 68, and said plate is provided with two levers 69, which are pivoted as 70. These two levers 69 are disposed on opposite sides of the plate 68, and pivotally secured to the plate, as at 71, is a lever 72, which is provided with a finger portion 73. This lever 72 is provided with a rigid member 74, which passes through an opening 75 in the plate 68 in such a manner that as said lever is depressed, the two levers 69 will be rocked about their pivotal points 70, in which position the openings in said levers 69, which receive the rods 60 and 61, will be in alignment with said rods and permit a free movement of the plate 68 therealong.

By this construction, it will be readily apparent that by depressing the lever 73, the plate 68 is free to move along the rods 60 and 61, and that it will be moved by said lever. When, however, the lever 73 is released, under the influence of the springs 69, the levers 69 assume an angular position with respect to the plate 68 and the rods 60 and 61. With the parts in this position, if the rod 60 be reciprocated, it will move through its respective lever 69 freely, but when the rod is released and it returns to its normal position under the influence of the spring 65, the plate 68 is moved with it to move the marker longitudinally of the supporting bed. In order that the plate 68 may not move under the influence of the reciprocation of the rod 60, the rod 61 is gripped by its respective lever 69, which prevents the aforementioned action taking place. In this form of the invention, the means for adjusting the stroke of the rod 60 is positioned at the bottom of the supporting bed, and it consists of a tapered plate 80 slidably mounted at the lower end of the supporting bed. The plate 80 is provided with a right-

angular fitting 81 with which a screw-threaded bolt 82 engages in such a manner that as the bolt is rotated by its head 83, the tapered plate 80 is adjusted relatively 5 to the head 67 of the rod 60 to increase or decrease the length of the stroke of said rod.

From the foregoing, it will be apparent that the present invention provides a copy holder in which a step-by-step movement 10 of the marker is obtained by a novel and simple construction, and, at the same time, a mechanism of this character which is positive in operation and adaptable to copies 15 having different spaces between the lines, is also provided.

What is claimed is—

1. A copy-holder comprising a base, a writing bed carried by the base, a plurality 20 of rods rigidly carried by the writing bed on the rear face thereof, a reciprocating rod mounted on the rear face of the writing bed, said reciprocating rod being movable longitudinally of the writing bed, a carriage 25 slidably mounted on the first-mentioned rods and overlying the reciprocating rod, a lever pivotally carried by the carriage, a trigger member pivotally carried by said lever and provided with an opening for the 30 reception of the reciprocating rod, and means actuating the trigger to cause its positive engagement with the reciprocating rod when the latter is moved in one direc-

tion and to permit of free movement of the reciprocating rod in the other direction. 35

2. A copy-holder comprising a base, a writing bed, a pair of spaced guide rods rigidly secured to the rear face of the writing bed, a reciprocating rod mounted on the rear face of the writing bed, a carriage mov- 40 able on the rigid rods and overlying the reciprocating rod, and means carried by the carriage and adapted for engagement with the reciprocating rod whereby the rod is free to be reciprocated in one direction, 45 said means serving to move the carriage upon reciprocation of the rod in the other direction.

3. A copy holder comprising a base, a writing bed carried thereby, a plurality of 50 rigid rods carried by the writing bed, a reciprocating rod carried by the writing bed, means for automatically reciprocating said rod in one direction, a carriage carried by the rigid rods, means carried by the carriage 55 for engagement with the reciprocating rod, said means being pivotally mounted on the carriage to permit of free movement of the reciprocating rod in one direction and provided for movement of the carriage upon 60 reciprocation of the reciprocating rod in the opposite direction, and a member movable transversely of the writing bed for limiting the movement of the reciprocating rod in one direction.

ALBERT N. WOODRUFF.
